UNITED STATES PATENT OFFICE.

MARION G. SLAWSON, OF GIRARD, KANSAS.

GRAVE MARKER.

Application filed May 27, 1927. Serial No. 191,674.

This invention relates to grave markers and it has for its object to provide an improved construction for a device of this character, whereby marked economy in manufacture will be effected, simplicity and ease in its use will be achieved, and the maximum of protection will be afforded to the data card therein, so that the entry of rain or snow, to said card, either directly or under the capillary action of water, will be prevented.

Further objects and advantages of the invention will be set forth in the detailed description which follows.

15 In the accompanying drawings:

Figure 1 is a front elevation of a grave marker constructed in accordance with the invention.

Figure 2 is a rear elevation thereof.

20 Figure 3 is a front elevation of the marker with the cover shield thereof swung upon its hinge to open position.

Figure 4 is a partial vertical sectional view through the structure of Figure 3, with the cover shield in closed position.

Figure 5 is a fragmentary sectional view upon line 5—5 of Figure 3, and

Figure 6 is a horizontal sectional view upon line 6—6 of Figure 2.

30 Like numerals designate corresponding parts in all of the figures of the drawing.

The grave marker of the present invention comprises a metallic plate 5, which is preferably stamped from sheet metal to channel formation. In the stamping of this element the metal is so shaped as to form a loop 6 and a pocket 7, these elements serving to, respectively, receive the lower end 8 and a tongue 9 of a metallic cross 10. The upper end of the stake is cut away at 11 upon each of its upper corners and the material between said cut away portions is bent to form an eye 12, which constitutes one element of a hinge by which a cover shield 13 is hingedly connected to the upper end of the stake. To this end the metal of the cover shield is cut out, as indicated at 14, and said metal is bent to roll formation to form a pintle 15 (see Figure 4) said pintle being received within the eye 12.

A card holding frame 16 is secured by the countersunk rivets 17 to the face of the stake 5, and is provided with turned over edges 18, forming channels for the reception of a data-bearing card 19, and a glass plate

20, by which said card is covered. The lower edge of the card 19 bears upon lips 21 that are struck from the metal of the card carrying plate, while the lower edge of the glass plate 20 rests upon lips 22. Thus it 60 will be seen that the lower edge of the card is supported a material distance above the lower edge of the glass. By virtue of this construction, coupled with the overturned protecting edges 18, the entry of rain, snow, 65 or other moisture, to the data bearing card is effectually prevented. Where the lower edge of the card and the lower edge of the glass coincide, or substantially so, it has been found that the water will travel up to 70 the card by capillary action even when it cannot reach the card directly, and it is to prevent this injury to the card by such capillary action of the water that the lips 21 are so related to the lips 22 that the card 75 will be held a material distance above the lower edge of the glass. The rear face of the cover shield is recessed as indicated at 23, for the reception of the card carrying structure, and in the stamping of the cover 80 shield, lips or ridges 24 are struck up from the edges of the recess 23, said lips being adapted to engage over teats 25, formed upon the corresponding portion of the card carrier. Thus, when the cover shield is 85 pressed upon the card carrier to the position illustrated in Figure 4, the teats 25 will snap behind lips 24, and the parts will be held in closed position without other fastening.

90 The cover shield is provided with a sight opening 26 through which the data upon the card 19 is visible when the shield is in closed position. The pocket 7 is provided with an opening 7^a at its lower end so that rain cannot stand therein.

It is to be noted that substantially all of the parts, and in fact, all of the parts except the card, glass and rivets are made from metal stampings, and that the hinge, the 100 fastening means for the shield, and the supporting means for the card and glass, are all secured by proper treatment of such stampings to strike them out at the proper points. It will further be observed that the hinge 105 does not project above the top of the cover shield when the latter is in lowered position, and that it does not project rearwardly of the line of the stake. Therefore, it does not interfere with the proper placement of the 110

cross, nor does it mar the symmetry of the shield.

It is to be understood that the invention is not limited to the precise construction set forth but that it includes within its purview whatever changes fairly come within either the terms or the spirit of the appended claims.

Having described my invention, what I claim is:

1. In a grave marker a card carrying element having a channeled top and a channeled side, and an open lower side, and means for supporting a card and glass therein with the lower edge of the card a material distance above the lower edge of the glass.

2. The combination with a supporting stake, a card carrying plate secured thereto having closed and channeled sides and top, and an open lower side, and means projecting forwardly from the rear wall of the card carrier adapted to engage beneath the lower edge of a card, and additional means projecting forwardly from the rear side of the card carrier adapted to engage the lower edge of a glass, the first named means being spaced a material distance above the last named.

3. The combination with a supporting stake, the material of which is cut at the top of said stake to form an eye, a cover shield the material of which is cut at the central portion of its top to form a pintle adapted to engage with said eye, said cover shield having a recessed rear face, and a sight opening, a card carrying frame secured to the stake having closed side and upper edges, a card and glass in said frame, means for supporting the card and glass in the frame with the lower edge of the card a material distance above the lower edge of the glass, and interengaging fastening devices between the side walls of the recess and the side walls of the card carrying frame.

4. A structure as recited in claim 3, wherein said fastening devices are formed by suit-

ably striking out the material of the respective parts.

5. The combination with a supporting stake, of a card carrying frame secured to the stake having closed side and upper edges, and an open lower edge into which a card and glass plate may be slipped by upward movement, and a cover shield hinged to the stake having a recessed rear wall, into which the card carrying frame enters when the cover shield is moved to closed position.

6. A structure as recited in claim 5, in combination with complementary frictionally engaging fastening elements upon the cover shield and card carrying frame for holding the cover shield in locked position.

7. A structure as recited in claim 5, in combination with interengaging projections upon the end walls of the card carrying frame and the recessed portion of the cover shield, which snap past each other to form a frictional lock when the cover shield is moved to closed position.

8. A device of the character described made of stamped sheet metal and comprising a stake of channeled formation, a card carrying frame fixed to the stake comprising a flat rear wall and overturned channeled side and upper edges, a card and glass adapted to fit in said frame with the lower edge of the card above the lower edge of the glass, a cover shield hinged to the top of the stake having a sight opening formed therein and a recessed rear face around said sight opening, the walls of the recessed portion carrying locking means adapted to engage with complementary locking means upon the card carrying frame, the top and side edges of the card carrying frame entering the recessed portion of the cover shield, and that portion of the cover shield constituting the edge of the sight opening contacting with the glass.

In testimony whereof I affix my signature.

MARION G. SLAWSON.
